UNITED STATES PATENT OFFICE.

FREDERICK FITT, OF OTTAWA, ONTARIO, CANADA, ASSIGNOR OF A PART
OF HIS RIGHT TO JOHN RUTHERFORD ARMSTRONG AND HENRY JAMES
GIBBS, OF SAME PLACE.

REMOVABLE ESCAPEMENT FOR WATCHES.

SPECIFICATION forming part of Letters Patent No. 230,262, dated July 20, 1880.

Application filed February 9, 1880.

To all whom it may concern:

Be it known that I, FREDERICK FITT, of Ottawa, in the county of Carleton, Province of Ontario, Canada, have invented certain Improvements in Watches, of which the following is a specification.

My invention relates to watches having the escapement mounted wholly upon an independent detachable bed or plate, and is designed as an improvement upon the device for which Letters Patent were granted me bearing date August 24, 1875, and numbered 167,089, the improvements consisting in a peculiar form and arrangement of parts and location of the fastening-screw, whereby the adjustment and securing of the escapement are rendered more accurate and speedy, the employment of any desired form of escapement permitted, and all danger of disarrangement avoided.

In the accompanying drawings, Figure 1 is a face view of the watch-movement; Fig. 2, a similar view with the escapement removed; Fig. 3, the escapement detached from the movement; Fig. 4, the escapement-platform with the escapement removed therefrom; Fig. 5, the reverse or back face of the escapement-platform; Fig. 6, a face view of the dial side of the pillar-plate, showing the automatic stop and attendant parts; Fig. 7, a cross-section on the line *x* *x* of Fig. 1, showing more clearly the action of the automatic stop; Fig. 8, a view of the stop-lever detached; Fig. 9, views representing certain screws hereinafter described; Fig. 10, a view of the escapement-platform detached furnished with a straight-line escape-

ment. Under the construction shown in my former patent (above referred to) considerable difficulty was encountered in adjusting the escapement, and occasionally the fastening-screw, striking the face of the detent-lever instead of its edge, would force the same before it, instead of causing it to swing upon its pivot, thereby deranging the parts. The location of the fastening-screw under the former construction and arrangement was also found inconvenient and objectionable, for the reason that it prevented

the use of an angular or chronometer escapement, and by its proximity to the escape-wheel subjected the latter to great danger of injury through the slipping of the tool by which the fastening-screw was turned home.

My present improvements are designed to overcome these difficulties; and to this end I adopt the construction and arrangement shown in the accompanying drawings, in which—

A represents the pillar-plate, and B the escapement-platform, having at one end a projecting lip or thin edge, *a*, and carrying the balance-cock *b*, the cock-prop being secured in place by a screw, *c*, preferably formed with a polygonal head to facilitate its removal by pliers or tweezers.

d represents the pallet and escape-wheel bracket, also mounted upon the escapement-platform and secured thereto, *e* indicating the balance-wheel, *f* the pallets, and *g* the escape-wheel.

The several parts being thus mounted and secured upon the platform B, it will be seen that in order to remove the escapement it is only necessary to detach the platform from the pillar-plate, when all may be lifted off.

The manner of securing the platform to the pillar-plate is susceptible of modification; but in practice the arrangement illustrated in the drawings is preferred.

As shown in Fig. 5, the platform B is furnished on its under face with three small projecting studs, *h* *i* *j*, which serve as steadyng-pins, the pin or stud *h* being the most important, as it serves to insure and maintain the proper depthing of the teeth in the escape-wheel pinion. These studs serve to prevent the shifting of the escapement-platform B, which is firmly secured to the pillar-plate by a single screw, *k*. It will be observed by reference to the drawings that this screw *k*, instead of being located as in the patent above referred to, is located in rear of the balance-cock, which is thus made to serve as a guard to protect the parts of the escapement against injury through the slipping of the tool by which the screw is inserted. This location of the screw is especially important, however, in that it permits

the use of an angular or a chronometer escapement, which could not be used under the former arrangement of parts.

In order that there may be no possibility of the platform B rocking or tipping, a flanged screw, *l*, is screwed into the pillar-plate in such position that when the platform is in place its edge or lip *a* shall extend under the flange of the screw, as shown in Fig. 1.

10 The screw *l* need not be removed from the pillar-plate in detaching the escapement-platform; as a very slight backward turn is sufficient to release its hold upon the lip *a*.

From the above it will be seen that to remove the escapement it is only necessary to loosen the screw *l* and remove the screw *k*, when the platform B, with all its attendant parts, may be lifted off.

In order that the connection with the fourth wheel may be easy, the edge of the platform B is recessed, as at *m*, to fit or pass thereunder, a similar recess, *n*, being formed on the other face of the platform to accommodate the center wheel, while a projection or lip, *o*, at 25 the inner side of the platform B, serves as a convenient hold for the fingers in handling.

The stop or locking device which locks the train automatically upon the detachment of the escapement is represented in position in 30 Figs. 6 and 7 and detached in Fig. 8, it being controlled in its action by the screw *k*, which holds the platform B in place. While it is preferred to thus control the action of the stop, it is apparent that other means for actuating 35 the same may be employed.

The stop or detent consists of a pin, *p*, passing through a slot or opening, *q*, in the pillar-plate A, and arranged to engage with or be disengaged from the teeth of the fourth wheel, 40 C, said pin being carried upon a pivoted or swinging lever, D, as shown in Figs. 6 and 8. The lever D is free to swing or turn upon a shouldered pivot-screw, *r*, and has its outwardly-projecting end shouldered and arranged to work into or through a recess in the outer rim or edge of the pillar-plate, said end being urged outward by a spring, the click-spring *s* being preferably made to serve also 45 this purpose.

50 As more clearly shown in Fig. 9, the screw *k*, by which the escapement-platform is held in place, is formed with a tapering or pointed end, and, as shown in Figs. 6 and 7, this

pointed or tapered end is passed through the pillar-plate almost exactly over the outer edge 55 of the long arm of the lever D, so that as the screw is turned to its seat the point is caused to press inward the long arm of the lever, thereby causing the short arm to move outward and disengage the pin *p* from the teeth 60 of the fourth wheel, C, and to hold it away therefrom, while the withdrawal of said screw permits the lever D, pressed by the spring *s*, to move in the reverse direction and to lock the fourth wheel. It will thus be seen that it is 65 impossible for any injury to occur to the train in removing the escapement.

By arranging the end of the lever D to work in the recess in the rim it is prevented from being pressed outward from the face of the 70 pillar-plate, while the shoulder *y* prevents the lever from being moved too far.

By referring to Figs. 3 and 10 it will be seen that either a straight-line or angular escapement may be with equal facility used in my 75 construction, and the same is true with reference to pocket-chronometers, whether the escapement be of the English or the Swiss pattern.

Having thus described my invention, what 80 I claim is—

1. In combination with the pillar-plate provided with the flanged screw *l*, the platform B, having the lip *a* and stud *h*, and secured to the pillar-plate by a screw, *k*, as described. 85

2. The combination of the lever D, click-spring *s*, and screw *k*, substantially as and for the purpose described.

3. In combination with a pillar-plate having a recessed rim, the lever D, having its end 90 shouldered and working in said recess, and the screw *k*, all arranged and operating substantially as described.

4. The escapement-platform B, provided with the lip *a*, recesses *m n*, and projection *o*, 95 as shown.

5. In combination with the pillar-plate of a watch, a detachable escapement-platform and a fastening-screw located in rear of the balance-cock, whereby the cock is made to protect the escapement and the use of an angular or chronometer escapement is permitted. 100

FREDERICK FITT.
